UNITED STATES PATENT OFFICE.

FREDERICK G. KEYES, OF BOSTON, MASSACHUSETTS, ASSIGNOR TO COOPER HEWITT ELECTRIC COMPANY, OF HOBOKEN, NEW JERSEY, A CORPORATION OF NEW JERSEY.

QUARTZ LAMP.

1,197,829.

Specification of Letters Patent. Patented Sept. 12, 1916.

Application filed February 10, 1913. Serial No. 747,315.

To all whom it may concern:

Be it known that I, FREDERICK G. KEYES, a citizen of the United States, and resident of Boston, county of Suffolk, State of Massachusetts, have invented certain new and useful Improvements in Quartz Lamps, of which the following is a specification.

Various constructions have been proposed for mercury vapor lamps operating at high temperatures or pressures, usually requiring the use of a transparent tube or container having a high resistance to heat and exemplified by quartz or by such kinds of glass or combinations of glass and quartz as approach in this respect the qualities of quartz. Such lamps are here comprised under the term quartz lamps and my invention relates to improvements in this type of apparatus. It has been customary in the manufacture of such lamps heretofore to provide an anode, usually of mercury, more or less freely exposed to the interior of the tube throughout a considerable extent of surface, while the cathode has been contained in a chamber having a somewhat narrowed opening into the main lamp tube whereby the point at which current shall proceed from the cathode is localized within comparatively narrow limits. At the same time, the mercury or other vaporizable material constituting the electrodes has been provided with means for automatically maintaining the proper distribution of the electrode material between the electrodes during normal operation, without the physical transfer of electrode material in liquid form from one electrode to the other. It is a matter of importance in the construction of lamps of this class to reduce to the lowest possible safe limits the amount of quartz entering into the lamp construction, quartz being an expensive material. It is also important to reduce the necessary manipulation of the quartz, since the handling thereof and building up of various parts requires successive treatments from a source of heat, such as the oxy-Blau-gas flame. This again tends to reduce the cost of manufacture by a considerable item.

I have devised means for localizing the passage of current out of the cathode, where the "cathode spot" is produced, and at the same time I produce a lamp requiring considerably less material in the containing

body and a smaller amount of treatment by 55 the oxy-Blau-gas flame or other source of heat.

My invention will be understood by reference to the accompanying drawings in which—

Figure 1 is a side elevation of a lamp embodying my invention and, Fig. 2 is a plan view of the same lamp.

Referring to the drawing, 1 is a light-transparent tube forming the main body of 65 the tube or container; 2 is a mercury anode, and 3 a mercury cathode, while 4 is a condensing chamber for the anode, and 5 a cooling chamber for the cathode. Suitable seals, 6, 6, here represented merely as types 70 of efficient seals, are provided with platinum leads, 7 and 8, passing, respectively, to the anode 2 and the cathode 3.

The anode end of the apparatus shown exhibits no features of special novelty, but 75 the opposite end containing the cathode is novel in certain respects. At this end of the lamp, the tube, 1, is joined to a transverse tube, 9, wherein the major portion of the negative electrode material is contained, 80 During operation of the lamp, an exceedingly high temperature is developed at and near the point where the current flow from the cathode takes place and it has heretofore been customary to reinforce the 85 end of the lighting portion of the quartz tube by building it up by successive treatments in the process of manufacture. Instead of doing this, I provide as a part of the said light-giving tube a disk, 10, of 90 quartz, sealing off one end of the tube, except at an opening, 11 (usually centrally located), having a boss, 12; as shown in the drawings.

By virtue of this construction, the cathode 95 spot is developed at the surface of the mercury within the opening 11 and in practice I have found that the construction is effective for the purposes intended and that the cost of material and cost of manufacture have 100 been materially reduced in the production of the lamp. The boss 12 combined with the opening 11 constitutes what is practically a tube within one end of which the mercury of the cathode is adapted to lie. By varying 105 the thickness of the tubular portion, thus formed, the degree to which this tube becomes heated may be governed and thus the

capacity of said tubular portion for conducting heat to the mercury may be varied. In general, a rather heavy wall is desirable at this point.

5 By the use of the perforated disk construction, 10 and 11, supplemented by the boss 12, sufficient freedom is given to the movements of the cathode mercury in the tube formed by the boss and its perforation 10 to permit a crowding back of the mercury or a forward movement thereof until, as the level of the active electrode 3 becomes more or less remote from intimate contact with the cooling power of the cathode chamber 5 15 its temperature will become higher or lower as the case may be with the consequent adjustment of the evaporation of the mercury to compensate for an excessive or defective cooling capacity of the cathode chamber 20 so that there is no further gain or loss of mercury at the cathode.

I claim as my invention:

1. In a vapor electric apparatus, a tubular portion of quartz providing a vapor path 25 and terminating at one end in a cooling chamber, a cathode in said chamber, a transverse partition separating the end of the tube from the chamber, the said partition being provided with an opening having a 30 reinforced edge perforation.

2. In a vapor electric apparatus, a tubular portion of quartz providing a vapor path and terminating at one end in a cooling chamber, a cathode in said chamber, a 35 transverse partition dividing the end of the tube from the chamber, the said partition being provided with an opening and a boss surrounding the said opening.

3. In a vapor electric apparatus, a tubular portion of quartz providing a vapor path 40 and terminating at one end in a cooling chamber, a cathode in said chamber, a transverse partition dividing the end of the tube from the chamber, the said partition being 45 provided with an opening, and a boss hav-

ing a thick wall surrounding the said opening.

4. In a vapor electric apparatus, a tubular portion providing a vapor path and terminating at one end in a cooling chamber, a 50 cathode in said chamber, and a transverse partition between the tube and the chamber, the said partition being provided with an opening, and a boss surrounding said opening. 55

5. In a vapor electric apparatus, a tubular portion providing a vapor path and terminating at one end in a cooling chamber, a cathode in said chamber, and a partition between the tube and the chamber, the said 60 partition being provided with an opening, and a boss surrounding said opening, the outer edge of the boss being exposed to the cooling influence of the cathode material, and the inner end thereof being open to the 65 interior of the tube.

6. In a vapor electric apparatus, a tubular portion of quartz providing a vapor path and terminating at one end in a cooling chamber, a cathode in said chamber, a trans- 70 verse partition dividing the end of the tube from the chamber, the said partition being provided with an opening and being re-entrant in the direction of the anode.

7. In a vapor electric apparatus, a tubular portion providing a vapor path and terminating at one end in a cooling chamber, a cathode in said chamber, and a transverse partition integral with the tubular portion between the tube and the chamber, the said 75 partition being provided with an opening and being re-entrant in the direction of the anode. 80

Signed at New York in the county of New York and State of New York this 7th day 85 of February, A. D. 1913.

FREDERICK G. KEYES.
